CLAIM

The ornamental design for a hook, as shown and described.

DESCRIPTION

FIG. 1 is a front, side and top perspective view of a hook showing our new design;

FIG. 2 is a front elevational view thereof;

FIG. 3 is a side elevational view thereof;

FIG. 4 is a rear elevational view thereof;

FIG. 5 is a top plan view thereof; and,

FIG. 6 is a bottom plan view thereof.

The broken-line disclosure of elements in the views is for illustrative purposes only and forms no part of the claimed design.
